ELECTRONIC DISCHARGE TUBE

Annemarie Katsch, Berlin-Lichterfelde, Germany, assignor to C. Lorenz Aktiengesellschaft, Berlin-Tempelhof, Lorenzweg, Germany, a company

Application January 16, 1937, Serial No. 120,895
In Germany January 16, 1936

3 Claims. (Cl. 250—27.5)

In the construction of electronic discharge valves or tubes glass bulbs are used in most cases to form the discharge vessel thereof. Glass vessels, however, on account of their high fragility 5 require to be handled very carefully when being manufactured as well as in the operation of said tubes.

Discharge vessels as provided by the invention are made with the aid of ceramic material and 10 comprise certain features of novelty which will appear from the following description and be particularly pointed out in the appended claims, reference being had to the accompanying drawing that shows a partially diagrammatic sectional 15 view in a medial vertical plane of one embodiment of the invention.

In this drawing, A denotes the anode, K the cathode, G the grid which in the case represented by way of example is a wire helix whose turns E, F are supported by shanks E, F in a well known manner. These are fastened in a socket 3 of a 20 metal disc B, this disc thus supporting the grid G by means of the shanks E, F. Cathode K is arranged to extend through socket 3. Anode A has cooling fins W the two outer of which are each integral with a ring P.

The discharge vessel D is composed of ceramic portion W₁, W₂, W₃ and a glass top U. The portions W₁, W₂ are held together by a metal ring Q shrunk thereon. Equally, the portions W₂, W₃ are held together by the two rings P shrunk 25 onto them. Portion U is provided with a tubular extension u where the vessel is connected with the pump and where it is sealed off, as is well known with devices of this kind. Glass portion U is united with the ceramic portion W₃ by melting.

In order to provide for airtightness the ceramic portions W₁, W₂, W₃ are shaped outside by 30 grinding so as to intimately contact with the rings P, Q shrunk thereon. In this connection attention is called to the fact that the glass walls of discharge vessels do not allow of tooling them in this manner, especially because they are too thin in this regard. The airtightness afforded in 35 this way is raised to vacuum tightness by melting glass or a ceramic glazing or the like onto the butt joints so as to produce melting spots S.

The leads of the electrodes are sealed into the

wall of the vessel, except those portions thereof which are annular and are shrunk onto the vessel, such as the rings P.

Ring Q, or any other ring of similar disposition, may form one coating of a condenser C whose other coating is a metal ring 2, an annular dielectric 4 being arranged between the two.

In order to avoid that during the process of producing the melting spots S too much heat is carried away by the electrodes concerned, in accordance with the invention the path between the spots S and the main body or active part of the electrodes is made as large as possible. This should be done especially because the anode A has a relatively large mass. In the example represented this path is formed by the rings P and the outer cooling fin W integral therewith, thus being long enough to prevent the heat from being carried away to an extent that would impair the effect of the melting.

The invention is not only suitable for combining ceramic parts with metallic ones in order to form a vacuum vessel as described herebefore, but may be employed also whenever in a discharge tube metal parts are to be connected with ceramic parts. For instance, it is possible to support within the tube the electrodes thereof by means of ceramic studs or shanks and to shrink metal rings onto such ceramic members, these rings being in their turn connected to the electrodes proper. The ceramic studs or the like may likewise be formed integral with the vacuum vessel.

Discharge tubes as provided by the invention are much less liable to injury than those hitherto known and besides are easy to manufacture.

What is claimed is:

1. An electronic discharge tube having a ceramic vessel, electrodes in said vessel, and a ring integral with one of the electrodes located outside and shrunk on the vessel.
2. A discharge tube according to claim 1, the electrode leads of which extend directly through the wall of the vessel whereby the provision of a press is obviated.
3. A discharge tube according to claim 1, comprising a condenser having an element constituted by one of said metallic portions.

ANNEMARIE KATSCH.
